[57] **CLAIM**

The ornamental design for a baseball pitching device, as shown and described.

DESCRIPTION

FIG. 1 is a perspective view of a baseball pitching device showing my new design;

FIG. 2 is a front elevational view thereof;

FIG. 3 is a right side elevational view thereof, the left side being a mirror image;

FIG. 4 is a rear elevational view thereof;

FIG. 5 is a top plan view thereof; and

FIG. 6 is a bottom plan view thereof.

The broken line showing of a baseball player, baseballs and a stand in FIG. 1 is for illustrative purposes only and forms no part of the claimed design.

FIG.-1

FIG. 6

FIG. 2

FIG. 5

FIG. 4
